UNITED STATES PATENT OFFICE.

LEO SIMMONS, OF WASHINGTON, DISTRICT OF COLUMBIA.

FLUSHING VALVE.

Application filed December 11, 1922. Serial No. 606,279.

To all whom it may concern:

Be it known that I, LEO SIMMONS, a citizen of the United States of America, and a resident of Washington, District of Columbia, have invented certain new and useful Improvements in and Relating to Flushing Valves, of which the following is a specification.

This invention relates to that type of flushing apparatus wherein the flushing valve mechanism is elevated or opened manually while dash pot mechanism is provided to automatically control the closing movement of the valve mechanism and approximately predetermine the quantity of water discharged at each flushing operation.

An object of the invention is to produce a simple and durable flushing apparatus of an improved character which will be efficient and reliable in action and compact and economical in construction.

A further object of the invention is to provide flushing apparatus that embodies a flushing-operation-controlling dash-pot mechanism having improved regulating means, and that involves an advantageous arrangement with respect to the flushing water passage.

A further object of the invention is to improve certain details of construction. With these and other objects in view my invention consists in certain novel features in construction and in combinations and arrangements, as more fully and particularly set forth and specified hereinafter.

Referring to the accompanying drawings:

Fig. 1 is a longitudinal vertical section of flushing apparatus embodying my invention, certain parts being shown in part in elevation.

Fig. 2 is a detail section on the line 2—2, Fig. 1.

Fig. 3 is a detail vertical section of the dash pot mechanism, the piston being shown in elevated position to admit water to the dash pot, cup, or cylinder, as when the flushing valve mechanism is elevated or completely opened.

Fig. 4 is a detail section on the line 4—4, Fig. 1.

Fig. 5 is a detail elevation of the upper end of the dash pot cup to show, particularly, the radial water inlets.

In the particular example illustrated, the casing of my flushing apparatus is approx-

imately in the form of a straight vertical tube or cylinder, having a lateral water supply inlet at its upper end, and being open at its lower end for vertical downward flow of flushing water therefrom.

In this particular example, the casing is composed of three tubular casing sections arranged end to end in longitudinal alignment, namely, the top end section 1, that provides the internal pressure water supply chamber *a*, and the intermediate section 2, and lower end section 3, that provide the flushing water passage *b*, and carry the manual valve opening means and the dash pot cup or cylinder and its regulating means.

The tubular top section is formed with a lateral radial water supply inlet, located intermediate its upper and lower ends, and in this instance extending into chamber *a*, through exterior boss 1^a that is internally threaded to receive the pressure water supply pipe 4 from which water under pressure or head is delivered for flushing purposes. The lower end of section 1 is formed or provided with annular internal contraction to provide an annular internal seat and vertical flushing water outlet port *c*. A suitable annular packing washer 5 is located on said seat to form an annular valve seat having its center port alined with port *c*.

This washer 5 is held to its seat by a removable vertically adjustable spider consisting of horizontal ring 6 resting on the top face of the washer 5 and slidably fitting the inner surface of the casing section, and spaced vertical arms or uprights 6^a longitudinally and slidably engaging the inner surface of the section and at their upper ends abutting the under surface of a vertically adjustable ring nut 7, screwed longitudinally into the internally threaded upper end of section 1. When the upper end of the section is open, the ring nut can be unscrewed therefrom and the spider 6, 6^a, removed from the casing. The parts can be also assembled in the casing section, and when assembled the nut can be manipulated to tighten or loosen the pressure of the spider ring on the washer. The washer can thus be adjusted or removed through the upper end of the casing.

In this instance, the open upper end of the top casing section, is tightly closed and sealed by an exterior screw cap or end closure 8 removably meshing with exterior

- 6 screw threads at the upper end of the casing section. This cap 8 is formed with the exterior top nut or wrench hold 8^a to which mechanics can apply tools when 10 tightening up and unscrewing the cap. As the exterior surface of the cap will be damaged and marred by such tools, if such cap is exteriorly plated and ornamentally finished, I prefer to leave the cap exteriorly 15 in the rough or unfinished, and to cover the same by a removable finished ornamental cap 9, all as set forth and claimed in my copending application filed Nov. 29, 1922, Ser. No. 604,113.
- 15 The several casing sections 1, 2, 3, are removably joined together by screw threaded connections. For instance, the lower end of the top section 1 is formed with a depending reduced exteriorly threaded end that screws 20 into the internally threaded upper end of the intermediate section 2, and the lower section 3 has a reduced exteriorly threaded upper end that screws into the lower end of the intermediate section, so that the vertical 25 port or discharge passage *c* from the top section 1 opens and discharges longitudinally into the upper end of section 2; the interiors of sections 2, 3, forming the vertical flushing water passage *b*, in longitudinal 30 continuation of port or passage *c*, and discharging vertically at the lower open end of section 3.
- 35 The lower end of section 3 is formed for coupling to the flushing water pipe 10 that leads to the toilet or article to be flushed, so that the upper end of said pipe 10 forms a longitudinal downward continuation of the straight vertical flushing valve casing, whereby certain advantages are gained.
- 40 The passage of flushing water through the washer 5 and passage *c*, from chamber *a* to chamber *b*, is controlled by main lift valve 11 and auxiliary or pressure-relief lift valve 12, and these valves are controlled by lift rod or stem 13, as described in detail in my hereinbefore mentioned pending patent application.
- 45 The valve 11 is of conical formation, of metal or other suitable material, to seat down on washer 5 and normally close the passage therethrough. This valve has a vertical longitudinal pressure relief bore through which the lift rod 13 loosely extends. The auxiliary valve is of conical 50 formation and is operatively secured to and carried by the lift rod to normally seat on washer 11^a carried by the main valve 11, and close the water passage therethrough. The main valve 11 carries an upwardly projecting open frame or spider 11^b extending over the auxiliary valve and limiting the independent upward movement of the auxiliary valve with respect to the main valve, to permit pressure relief opening movements of the auxiliary valve until said valve

strikes the upper end of spider 11^b whereupon the main valve is lifted by and with the auxiliary valve, all by upward movement of the lift rod or stem 13. The main valve will thus be suspended from the auxiliary valve while the main valve is in open position.

55 The lift rod is straight and vertical and is arranged centrally and longitudinally within the casing and depends from the valves 75 into the casing sections 2, 3.

60 In this instance, the casing section 2 carries the manually operated means for lifting the stem 13 to elevate or open the valves. For instance, I show casing section 2 formed with a hollow lateral enlargement or bulge through which a horizontal rock shaft or spindle 14 extends and in the walls of which it is mounted to oscillate or rock. This spindle traverses the interior of the casing 85 to one side of the lift stem 13, and extends to the exterior of the casing where it is provided with any suitable readily accessible exterior handle 14^a, while within the casing, the spindle has operative lifting connection 90 with the stem 13, as by lateral lifting toe or finger 14^b at its free end engaging under a shoulder or abutment of the stem. The arrangement is such that the exterior handle 14^a can be rocked to lift the stem 13 and 95 open the valves, and then released and fall to normal position as the stem 13 descends, if so desired.

100 For instance, if so desired, the handle 14^a can be so arranged and the spindle 14 can be so operatively coupled to the lift stem 13 that the weight of the handle will be thrown onto the stem to aid in depressing the same. In the specific example shown, the lifting toe 14^b is forked to loosely straddle the stem 13, the stem being reduced at opposite side faces for the passage of the toe and to provide upper and lower knife or V-shoulders or abutments 13^a, 13^b, between which the toe ends are loosely arranged so that when the handle is lifted the toe will be likewise lifted into stem and valve lifting engagement with the upper knife edges 13^a, and when the handle is released, the toe will drop into valve stem depressing engagement with the lower knife edges 13^b and thus the stem will sustain the depressing weight of the handle and toe until the valves have reached closed positions.

110 The valves are controlled on their closing movements by a dash pot mechanism, which 115 comprises a piston formed on the lower end of the stem 13 and a cup or cylinder within the lower end section of the casing and longitudinally aligned therewith. For instance, the lower end of stem 13 is formed with a piston head 15 that is reduced and screw threaded at its lower end to receive nut 16 by which cup washer 17 is clamped to the piston head. The skirt of the washer de- 120

125 130

pends and the nut forms a reduced lower end of the head within the washer skirt so that said skirt can contract in diameter to permit downward flow of water past the piston 5 under certain conditions.

The dash pot cup or cylinder 18 is vertically elongated and closed at its lower end, open at its upper end, and has a vertical wall or barrel that is imperforate and cylindrical, except as hereinafter recited.

This cup forms a fixed permanent part of the casing section 3 and is centrally and longitudinally arranged therein in longitudinal alinement with the lift valves and 15 their stem and receives the piston that moves vertically with the stem.

The arrangement is such that when the valves are completely opened and the stem is at its limit of vertical movement, the piston 20 ton will be located in the open upper end of the cup and the cup will be filled with water. When the stem and valve are released to descend, the cup washer of the piston will open within the cup and resist the 25 descent of the piston and the parts upheld thereby, except as the pressure in the cup below the piston is reduced by release of water from the cup.

The cup 18 is preferably cast with the section 30 or otherwise formed as a rigid or integral part thereof. The cup is of reduced exterior diameter with respect to the internal diameter of the casing section surrounding the same to provide a vertical water 35 passage of ample capacity within the casing section past and at the exterior of the cup. The cup is supported in fixed position within the casing section by several spaced radial webs 18^a traversing said water passage and 40 rigid with the cup and casing section and preferably arranged exteriorly of and at the lower end portion of the cup.

I utilize one of these cup supporting webs 45 18^a in providing for the regulating escape of water from the cup to control the descent of the piston and the closing movement of the flushing valve mechanism.

For instance, I drill or otherwise form a 50 radial hole or duct 20 from the exterior of the casing section 3 through one of the webs 18^a and into the lower end portion of the cup to provide the small lateral or radial outlet or discharge port 19 from the interior 55 of the cup, and I afford outlet into the flushing water passage, from port 19 and duct 20, by drilling or otherwise forming a vertical duct 21 through the top edge of the web into the intermediate portion of the duct 20. Water can thus flow from the lower end of 60 the cup through port 19, ducts 20 and 21 discharging into the flushing water discharge passage of the casing through the open upper end of duct 21. This arrangement also permits water to flow through the 65 upper end of duct 21 and enter the cup,

under the suction pull of the piston when on its upward stroke. This reversal of the direction of flow through the duct and port tends to clear the same of dirt and obstructions.

I provide means for regulating the discharge flow of water from the cup through said port and ducts, and thereby can control, to a nicety, the quantity of flushing water discharged at a flushing operation. For 70 instance, I tap the duct 20 to longitudinally receive a tapered end screw valve 22 having its head 22^a accessible at the exterior of the casing. The head 22^a is formed to receive any suitable implement by which the screw can be rotated to move inwardly and reduce the capacity of the discharge or move outwardly and increase the capacity of the discharge. If so desired the outer end of the 75 duct 20 can be countersunk as shown, to receive the head of the regulating valve screw.

In order to assure, the filling of the cup before the flushing valve mechanism is released to start the piston on its downward stroke, I preferably slightly internally flare or bevel the upper end of the cup, at 18^b, and if need be, provide radial inlet ports 18^c through the upper end thereof. The open upper end of the cup is directly below and alined with flushing water passage *c* and hence flushing water, will fall into the cup even before the piston reaches its limit of upward movement, and the pressure thereof will tend to contract the lower end of the cup washer skirt and permit flow of water into the cup to fill the same.

The stem 14 extends through and rotates in hollow bearing bosses 24 projecting laterally from the bulge of the casing section 2. One of these bosses is closed against liquid leakage by a screw cap and packing washer. The other end of the spindle extends beyond the opposite boss to receive the handle 14^a. This handle end of the spindle also extends through an adjustable nut or gland 25 that screws onto the boss and contains suitable packing material 26 surrounding the stem and compressed against the outer end of the boss to prevent liquid leakage along the spindle. Ordinarily, if the nut or gland is screwed up tightly enough to compress the packing and really prevent leakage under all conditions, the packing will exert such friction against movement of the spindle, as to prevent the free movement that I desire.

I have overcome this difficulty by forming an annular groove 28 in the spindle of such width longitudinally of the spindle as to extend into the bearing boss as well as beyond the same. I also preferably slightly enlarge the outer end of the bore or bearing of said boss, see 29, that surrounds the inner end of the groove 28 in

- the spindle. I find that the packing 26 will expand into the groove 28 and fill the same and will also extend into and fill the end enlargement 29 of the boss bore and thus effectively establish a barrier against liquid leakage around the spindle through the bearing boss bore, yet without applying such friction to the spindle as to prevent free movement and rotation thereof.
10. Claim is not herein made to the combination that includes the open frame or spider 11^b and tapered valve 12 radially spaced from said spider; nor to the combination that includes ring 6, arms 6^a, ring nut 7, and compression washer 5; nor to the combination that includes an annular groove in the handle spindle 14 into which packing, within screw cap 25, extends, as such combinations are claimed in my hereinbefore mentioned application for flushing apparatus filed Nov. 29, 1922, Ser. No. 604113.

It is evident that various changes, modifications and variations might be resorted to without departing from the spirit and scope of my invention and hence I do not wish to limit myself to the exact disclosures hereof.

What I claim is:—

30. 1. In combination, in flushing apparatus, a vertical tubular separable casing embodying an upper pressure water tubular section having a flushing water outlet port, an intermediate vertical tubular section receiving flushing water from said port and having a lateral hollow offset, and a lower vertical flushing water tubular section having a bottom flushing water discharge and provided with an internal vertical fixed open-top dash pot cup of relatively reduced external dimensions; a main flushing gravity lift valve in said upper section and controlling said port and having a pressure relief port; a vertical lift valve stem provided with a relief gravity lift valve controlling said pressure relief port, and arranged to control the closing movements of said valves and to lift the same to open said ports in succession, the lower end of said stem provided with a piston movable in said cup to control the gravity closing movements of said valves; and a rock shaft mounted in said offset and having an exterior operating handle and provided with a lateral vertically-swingable lifting finger within said intermediate section, the portion of the stem within said intermediate section formed with an upper transverse shoulder and a lower transverse shoulder, said finger arranged between said shoulders to engage the upper shoulder to lift the stem, and to bear down on the lower shoulder to aid in depressing the stem when said handle is released.
65. 2. In combination, in flushing apparatus,

a vertical tubular separable casing embodying an upper pressure water tubular section having a flushing water outlet port, an intermediate vertical tubular section receiving flushing water from said port and having a lateral hollow offset, and a lower vertical flushing water tubular section having a bottom flushing water discharge and provided with an internal vertical fixed open-top dash pot cup of relatively reduced external dimensions; a main flushing gravity lift valve in said upper section and controlling said port and having a pressure relief port; a vertical lift valve stem provided with a relief gravity lift valve controlling said pressure relief port, and arranged to control the closing movements of said valves and to lift the same to open said ports in succession, the lower end of said stem provided with a piston movable in said cup to control the gravity closing movements of said valves, and a lateral vertically-swingable lifting finger mounted in said intermediate section, and extending into said offset and having operating means extending to the extension thereof, the portion of the stem within said intermediate section formed with an upper transverse shoulder and a lower transverse shoulder, said finger arranged between said shoulders to engage the upper shoulder to lift the stem, and to bear down on the lower shoulder when said handle is released.

3. Flushing apparatus comprising in combination, a vertical tubular casing having a bottom flushing water outlet, said casing embodying three aligned tubular sections, the upper section providing a pressure water chamber, the two remaining sections providing a vertical water passage to said outlet, said upper section providing an outlet port to said passage, the lower section having a dashpot cup rigid therewith and centrally arranged therein and of reduced diameter to provide within said section an annular flushing water passage surrounding the cup, a web rigidly connecting the cup and traversing said annular passage, a main flushing lift valve and a pressure relief lift valve cooperating with said port, a vertical lift stem for said valves and at its lower end provided with a piston in said cup, means for operating said stem to lift said valves, said cup and said web having a water duct at one end open to said annular passage and at the other end open into said cup through a port in the vertical wall of the cup, said duct being formed in part by a hole extending radially from the exterior of the lower casing section through said web and into said cup, and a normally stationary screw valve in said hole and accessible from the exterior of the casing and longitudinally adjustable to control the water flow from said cup, said cup

and the piston formed against escape of water from the cup during the closing movement of said valves other than through said duct, the upper end portion of said cup being open to the descending flushing water, said cup and piston being formed to permit rapid filling of the cup on the upward movement of the piston.

4. Flushing apparatus comprising a casing providing an internal water pressure chamber having a bottom flushing water outlet port and a vertical flushing water passage having a bottom discharge, said outlet port discharging in the upper end of said passage, a dashpot cup vertically and centrally arranged in the lower part of the casing and of reduced exterior diameter with respect to the casing to provide within the casing an annular water passage surrounding the cup, spaced radial webs rigid with the casing and cup and extending across said annular passage, said cup having an open upper end below said outlet port, a hole being provided extending radially through the casing and one of said webs into the cup through a radial port in the vertical wall thereof, said web having a vertical water duct opening into said

annular passage and into said hole, a screw needle valve in said hole and accessible from the exterior of the casing and longitudinally adjustable to control the capacity of said radial port, flushing valve mechanism controlling said flushing water outlet port and embodying lift valves closed solely by gravity and water pressure, a lift stem operatively connected with said valves to control the closing movements thereof and provided with exterior handle actuated means for lifting the valves against gravity and water pressure, the lower end of the stem provided with a piston, said piston arranged in said dashpot cup, the piston and upper end portion of the cup being formed to permit quick filling of the cup, said piston and cup constructed and arranged to control the closing movement of said valves, the downward movement of the piston being controlled by the water outflow through said radial port, the walls of the cup below its upper end portion being otherwise imperforate.

Signed at Washington, D. C., this 9th day of December, 1922.

LEO SIMMONS.
